DESIGN FOR A TAPER ATTACHMENT CONVERSION RULE

William F. Groene and Harry F. Stoffregen, Jr.,
Cincinnati, Ohio, assignors to The R. K.
Le Blond Machine Tool Company, Cincinnati,
Ohio, a corporation of Delaware

Application May 21, 1943, Serial No. 110,256

Term of patent 14 years

To all whom it may concern:

Be it known that we, William F. Groene and Harry F. Stoffregen, Jr., citizens of the United States, and residents of Cincinnati, county of Hamilton, and State of Ohio, have invented a new, original, and ornamental Design for Taper Attachment Conversion Rule, of which the following is a specification, reference being had to the accompanying drawings, forming part thereof.

Figure I is a face view of a taper attachment conversion rule, embodying our new design.

Figure II is a face view of the front dial of the taper attachment conversion rule of Figure I.

Figure III is a face view of the underneath rotatable dial of the taper attachment conversion rule shown in Figure I.

We claim:

The ornamental design for a taper attachment conversion rule, substantially as shown.

WILLIAM F. GROENE.
